[57] CLAIM

The ornamental design for a key label, substantially as shown and described.

DESCRIPTION

FIG. 1 is a front elevational view of a key label showing my new design;
FIG. 2 is a rear elevational view thereof;
FIG. 3 is a left side elevational view, the right side being a mere image thereof;
FIG. 4 is a top plan view;
FIG. 5 is a bottom plan view;
FIG. 6 is a front elevational view of an alternate embodiment of the key label;
FIG. 7 is a rear elevational view thereof;
FIG. 8 is a left side elevational view thereof, the right side being a mere image thereof;
FIG. 9 is a top plan view; and
FIG. 10 is a bottom plan view.
